UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS SONS & MAXIM LIMITED, OF LONDON, ENGLAND.

SIGHTING APPARATUS FOR ORDNANCE.

No. 838,957.

Specification of Letters Patent.

Patented Dec. 18, 1906.

Application filed September 29, 1904. Serial No. 226,587.

To all whom it may concern:

Be it known that we, ARTHUR TREVOR DAWSON, lieutenant of the Royal Navy, director and superintendent of Ordnance Works, and 5 GEORGE THOMAS BUCKHAM, engineer, subjects of the King of Great Britain, residing at 32 Victoria street, Westminster, London, England, have invented certain new and useful Improvements Relating to Sighting Apparatus for Ordnance, of which the following is a specification.

This invention relates to sighting apparatus for ordnance.

As is well known, the graduations on a range-dial are ordinarily very close together at short ranges and more widely spaced at long ranges, thus rendering the sight-setting operation difficult to perform at short ranges, owing to the closeness of the graduations and 15 the consequent difficulty in reading them correctly. This is a disadvantage which it is the chief object of our invention to remedy, so that the graduations on the range-dial will be equal or approximately equal throughout. 20 For this purpose we interpose spiral-toothed gearing between the worm-gearing for actuating the range-dial and the sight-elevating rack comprising either a pair of toothed wheels gearing with each other or a single 25 toothed wheel gearing directly with the rack, so that the angular movement imparted to the range-dial by the sight-setting mechanism is regular or uniform or approximately 30 regular or uniform, notwithstanding the variable nature of the movement that has to be imparted to the elevating-pinion in changing the range.

In order that our said invention may be clearly understood and readily carried into 40 effect, we will describe the same more fully with reference to the accompanying drawings, in which—

Figure 1 is a side elevation of sighting apparatus provided with our improved sight-setting and range-indicating mechanism in 45 which two spiral-toothed wheels are employed. Fig. 2 is a side elevation showing the said sight-setting and range-indicating mechanism in which only one spiral-toothed 50 wheel is employed.

A is the usual bracket, which is affixed to the gun-mounting and to which the radial sight-bar A' is hinged at a, said sight-bar

having the usual laterally-displaceable pivoted holder or carrier a' for the telescopic or 55 other sight. B is the range-dial, and C the deflection-dial.

B^x is the sight-setting hand-wheel for elevating the sight-bar A' through the intervention of the gearing hereinafter described, 60 said hand-wheel being situated at the side of the sighting apparatus to permit of the latter being actuated by a separate sight-setter.

In Fig. 1 the range-dial B is mounted on 65 the same axle b as the worm-wheel b', which is actuated by the worm b², carried by the horizontal axle b³, with which the hand-wheel B^x is geared by means of bevel-gearing b⁴. b⁵ is the elevating-pinion for actuating 70 the sight-rack b⁶, said pinion being mounted on an axle b⁷, situated in close proximity to the said worm-wheel axle b. The axle b, carrying the worm-wheel b' and the range-dial B, is geared with the axle b⁷, carrying 75 the elevating-pinion b⁵, by means of two toothed wheels b⁸ b⁹, the pitch-lines of which are spiral. These two toothed wheels are so arranged that when the range-dial is at its zero position—i. e., the position in which it 80 is shown in Fig. 1—the largest diameter of the wheel b⁹ will be gearing with the smallest diameter of the wheel b⁸, and the form of the spiral is such that although the elevation of 85 the sight-rack is variable—i. e., diminishes at different parts of its movement in accordance with the increments of the range at which the gun is to be fired—the range-dial performs a regular or uniform movement, so that the degrees or graduations thereon for 90 indicating the elevation are equal or approximately equal throughout. When we use this arrangement, we sometimes arrange, for the sake of facilitating the sight-setting, 95 that one revolution of the sight-setting hand-wheel B^x gives, say, two hundred yards range indication on the range-dial, so that a quarter of a revolution of said hand-wheel would indicate fifty yards and a half-revolution would indicate one hundred yards on 100 the range-dial.

In the arrangement illustrated by Fig. 2 we dispense with the separate axles for the worm-wheel b' and the elevating-pinion b⁵ and employ only one axle—viz., the worm-wheel axle b, which also carries the range- 125

dial—and one spiral-toothed wheel b^9 . This toothed wheel takes the place of the elevating-pinion b^5 and gears with the sight-rack b^6 , which has the pitch of its teeth so arranged that the teeth will always remain in gear with the teeth of the spiral pinion b^9 . In the example illustrated in this case the divisions or graduations of the range-dial will not be absolutely equal throughout, but will only be approximately equal. They will, however, be such that their distance apart will be considerably greater at short ranges than is practicable with the usual sight-setting mechanism.

15. The range-dial revolves in a stationary ring B' , having a pointer B^2 .

What we claim, and desire to secure by Letters Patent of the United States, is—

1. In gun-sighting apparatus the combination of a sight-elevating rack, a range-dial, gearing for actuating said dial, and flat spiral-toothed gear interposed between the sight-elevating rack and the actuating-gearing and in a position parallel with the dial, for the purpose specified.

2. In gun-sighting apparatus the combination of a sight-setting rack, a range-dial, gearing for actuating said dial, and a plurality of flat spiral-toothed wheels engaging with each other, said toothed wheels being interposed between the sight-setting rack

and the actuating-gearing and in a position parallel with the dial, for the purpose specified.

3. In a gun-sighting apparatus the combination of a sight-setting rack, a range-dial, worm-gearing for actuating said dial and a plurality of spiral-toothed wheels engaging with each other and interposed between the sight-setting rack and the actuating-gearing for the purpose specified.

4. In gun-sighting apparatus the combination of a sight-elevating rack, a range-dial, an axle carrying said dial, a worm-wheel on said axle, a worm engaging with said worm-wheel, means for actuating said worm, a spiral-toothed wheel mounted on said axle, a second spiral-toothed wheel carried by an axle parallel to said dial-axle and gearing with the first-mentioned spiral-toothed wheel, and a pinion carried by the parallel axle for engaging with the sight-elevating rack, substantially as and for the purpose specified.

In testimony whereof we have hereunto set our hands, in presence of two subscribing witnesses, this 14th day of September, 1904.

ARTHUR TREVOR DAWSON.
GEORGE THOMAS BUCKHAM.
